UNITED STATES PATENT OFFICE.

EDMUND SAVAGE, OF ALBANY, NEW YORK.

AUTOMATIC COUPLING-PIPE FOR STEAM-HEATING SYSTEMS FOR RAILWAY-CARS.

SPECIFICATION forming part of Letters Patent No. 437,908, dated October 7, 1890.

Application filed April 2, 1890. Serial No. 346,275. (No model.)

To all whom it may concern:

Be it known that I, EDMUND SAVAGE, of the city and county of Albany, in the State of New York, have invented new and useful 5 Improvements in Automatic Coupling-Pipes for Steam-Heating Systems for Railway-Cars, of which the following is a specification.

My invention relates to improvements in coupling-pipes for conveying steam through 10 a train of railway-cars for the purpose of heating the latter; and the object of my invention is to provide means for automatically connecting and disconnecting the steam-pipes for supplying steam to a steam-heating system 15 of a train of railway-cars and for controlling the admission and exclusion of steam thereto simultaneously with the operation of coupling and uncoupling the cars which form said train. This object I attain by the means 20 illustrated in the accompanying drawings, which is herein referred to and forms part of this specification, and in which—

Figure 1 is a side elevation of the coupling-pipes of the conjoining ends of two railway-cars when in a disconnected condition. Fig. 2 is a like elevation of the same when the cars are coupled together. Fig. 3 is a plan view of one of said coupling-pipes, the car-coupler being removed to expose the under- 25 lying parts. Fig. 4 is a vertical section of the latter at the line X X. Fig. 5 is an end elevation of one of said coupling-pipes. Fig. 6 is a transverse section of Fig. 1 at the line Y Y, a portion of the bracket for holding the 30 coupling-pipe being shown in elevation; and Fig. 7 is an enlarged side elevation of a portion of the parts shown in Fig. 1.

To effect the object above named, my invention consists in providing the outer end 40 of each coupling-pipe with a head whose outer face is a flat vertical plane provided with a mortise and a corresponding dowel or tongue, which are so arranged that when two of said heads are brought face to face into 45 close contact the tongue of one will engage in the mortise of the other to produce an interlocking engagement of the two, the said heads being retained in close contact with each other by means of the car-couplers by 50 which the cars of the train are connected together and by means of compressible springs,

which are attached to each of said coupling-pipes; and my invention further consists in providing the coupling-pipes of a railway-car steam-heating system with automatic stop-cocks or valves, which are so arranged that the operations of connecting and disconnecting the cars will automatically effect the opening and closing movements of said cock or valve in a corresponding manner. 6c

As represented in the drawings, A indicates the lower part of a railway-car provided with bumpers 1 of any ordinary construction and having couplers 2, preferably of the usual form of interlocking hook, by which the operation of coupling is effected by bringing the cars together with a moderate degree of force. Said car-coupling mechanism forms no part of my present invention, and I do not limit myself to this precise form. 70

3 is a coupling-pipe for conveying steam from one car to another in a train of railway-cars, said pipes being adapted for coupling together to form a continuous system for supplying steam to the steam-heating apparatus 75 of a train of railway-cars. Said coupling-pipe is arranged in correspondence with the center line of the car, so that conjoining sections of said pipes will range in line with each other. The outer end of each coupling-pipe is provided with a head 4, which is connected thereto by a joint 5, which will permit said head to be deflected sidewise, so as to allow the cars to travel on curved tracks. Said head is made with a flat vertical face, and is provided with 80 a central opening 6, which contains a projecting semi-annular flange 7, that is fitted to enter the central opening of a conjoining head of the same form, and therein it will join with a like flange to form a tubular break-joint for 85 preventing the escape of steam through the joint between the two heads. The central opening 6 corresponds to the bore of the coupling-pipe 3, so that when two heads are in contact a connection of the steam-pipes of the conjoining cars is formed. In the outer face of the head a mortise 8 of any suitable form is made near one side of the central opening 6, and diametrically opposite to said mortise on the outer face of said head there is a projecting 90 tongue 9, of a form which corresponds to said mortise and whose outer part is tapered to 100

facilitate the engagement of the tongue in the mortise of a head that is to be conjoined thereto, and said mortises and tongues are so arranged that when two heads are brought 5 into interlocking contact the central openings of both will be in perfect accord. The joint 5 is formed of two similar parts that are joined horizontally, one of said parts being provided with an annular flange which is fitted into 10 the vertical opening of the other part, so as to form a break-joint for preventing the escape of steam. The two parts of said joint are held in close contact with each other by means of set-bolts 10 or other suitable means, which, 15 being centered to correspond to the center of motion of said joint, will permit the latter to be flexed sidewise.

The coupling-pipe 3 is fitted to freely slide endwise in a supporting-block 11, which is 20 carried in a hanger 12, which depends from the bottom of the car, the inner end of said coupling-pipe being provided with flexible joints, as hereinafter described, which will allow said pipe to slide endwise in said sup- 25 porting-block. The latter is provided with radial rods 13, which pass through slotted openings in said hanger, whereby freedom is afforded to said block to move vertically and laterally to suit any variable motion of the 30 coupling-pipes that may be produced by the motion of the cars. A spring 14 is provided for each radial rod 13, and is interposed be- 35 tween the sides of the supporting-block and the opening of the hanger for the purpose of normally holding the coupling-pipe in a cen- 40 tral position, said springs being adapted to yield when a strain is thrown upon the coup- 45 ling-pipe to move it in a transverse direction, either vertically or sidewise. The supporting- 50 block 11 is provided with a rearwardly-extending yoke 15, whereby the coupling-pipe is maintained in a level position during its vertical movements and which forms an abutment for a spiral spring 16, that encircles the coup- 55 ling-pipe 3, and the latter is provided with a collar 17 to receive the pressure of said spring, which operates to force said pipe endwise. The 60 coupling-pipe 3 is also provided with a stop-cock 18, which is normally retained in a closed position by means of a spring 19. Said stop-cock is provided with a lever 20, which when the 65 coupling-pipe is pushed inwardly as in the operation of coupling the cars, takes against an arm 21, projecting from the face of the 70 supporting-block appropriated to the coup- 75 ling-pipe in which said stop-cock is located, and thereby said stop-cock is automatically thrown open, and is retained in its open position by said arm during the time the cars re- 80 main coupled together.

The inner end of each coupling-pipe is pro- 85 vided with a joint-piece 22, which is jointed to said pipe by a transverse pivot 23, which will allow said joint-piece to swing in a ver- 90 tical plane. A second joint-piece 24 is jointed 95 by a horizontal pivot 25 to the swinging end

of the first joint-piece, the second joint-piece being dependent from the side of the first. The lower end of said second joint-piece is jointed by means of a horizontal pivot 26 to 70 a third joint-piece 27, which ranges longitudinally, and the latter is jointed by a vertical pivot 28 to an elbow 29, attached to the lower end of a vertical steam-pipe 30, which passes up through the bottom of the car to convey 75 the steam to the heating apparatus. The joint-pieces 22, 24, and 27 and the elbow 29 are all bored to form a continuous communication from the coupling-pipe 3 to the steam-pipe 30, and said joint-pieces render said com- 80 munication of sufficient flexibility to permit the coupling-pipes 3 to be pushed inwardly in the operation of effecting the coupling of the cars and the connecting of the coupling-pipes in the manner hereinbefore set forth. 85

The order of arranging the joint-pieces above set forth need not be strictly observed to produce the same effect, for it is obvious that the first joint-piece may be articulated to the inner end of the coupling-pipe so as to 90 swing in a horizontal plane, the third joint-piece being jointed to the elbow 29 so as to swing in a vertical plane. When preferred, the spring 19 may be omitted from the stop-cock 18, and in such cases the closing move- 95 ment of the latter will be effected by hand, but the opening movement of the same should be effected automatically, as herein described.

In the operation of coupling cars to form a train, when said cars are provided with my 100 invention, the heads 4 of the cars to be con- 105 joined will be brought into contact with each other before the couplers 2 of said cars be- 110 come interlocked, and after said couplers are fully engaged said heads will be retained in positive contact with each other by said cou- 115 plers during the entire time said engagement continues. When said couplers become dis- 120 engaged from each other, either accidentally or purposely, the contact of said heads will 125 not prevent the cars and coupling-pipes from being separated.

I am aware that automatic stop-cocks have heretofore been employed in coupling-pipes for railway-cars in such manner that the 130 opening movement of a stop-cock attached to one car has been effected by a device attached to a conjoining car, the coupling devices for said coupling-pipes being of different con- 135 struction on the opposite ends of the same car; but when so constructed it is necessary that the cars must be arranged so that the two unlike ends of the cars to be coupled will be brought together in order to effect the coupling. Thereby much confusion and a con- 140 sequent loss of time to get the cars in proper position is produced; but by my invention both ends of a car are provided with the same form of coupling. Therefore it is immaterial which end of the car is presented to a con- 145 joining car, and the opening movement of the stop-cock is effected by a device on the cor-

responding end of the same car to which said stop-cock is attached. I do not claim said earlier construction; but

What I claim as my invention, and desire to secure by Letters Patent, is—

- 5 1. The combination, with a coupling-pipe 3, having a head 4 articulated thereto in such manner that said head can be flexed sidewise, said head having a central opening that is 10 concentric with said pipe, a semi-annular flange 7, that is fitted to enter the central opening of a conjoining head of like construction so as to form, in conjunction with a like flange of said conjoining head, a tubular 15 break-joint for the two heads, each of the latter being provided with a mortise 8, and a projecting tongue 9, whereby said heads will be guided into interlocking positions with each other, of a car-coupling mechanism, 20 whereby the heads 4 of conjoining cars are retained in positive contact with each other, substantially as specified.
2. The combination of a coupling-pipe provided with a coupling-head which is articulated thereto, said head having a central opening that contains a projecting semi-annular flange, and said head also having a mortise and a corresponding projecting tongue, a hanger provided with a supporting-block in which said 25 30 coupling-pipe is fitted to slide endwise, said

supporting-block having a rearwardly-projecting yoke for retaining the coupling-pipe in a level position, oppositely-located springs interposed between the edges of said supporting-block on the sides of the opening in said 35 hanger for the purpose of centralizing said coupling-pipe, and a compressible spring interposed between the end of said yoke, and a collar secured to said coupling-pipe for the purpose of pushing said pipe outwardly beyond the end of the car, substantially as 40 specified.

3. The combination of a coupling-pipe fitted to receive an endwise movement and provided with a stop-cock, whose turn-plug is 45 provided with an operating-lever, and an arm or spur fixed to the corresponding end of the same car and adjacently to said stop-cock, said spur being held stationary in the path of the movement of said operating-lever in 50 such manner that when said coupling-pipe is pushed inwardly said operating-lever will act against said spur and thereby automatically effect the opening movement of said stop-cock, substantially as specified.

EDMUND SAVAGE.
